UNITED STATES PATENT OFFICE.

IDA M. SNYDER, OF LOUISVILLE, KENTUCKY.

DESIGN FOR A SHOE-HEEL PROTECTOR.

56,034.

Specification for Design.

Patented Aug. 10, 1920.

Application filed March 23, 1920. Serial No. 368,148. Term of patent 7 years.

To all whom it may concern:

Be it known that I, IDA M. SNYDER, citizen of the United States, residing at Louisville, in the county of Jefferson and State of Kentucky, have invented a new, original, and ornamental Design for a Shoe-Heel Protector, as shown in the accompanying drawing and described in the following specification.

Figure 1 is a perspective view of a shoe heel protector, showing my new design, and

Fig. 2 is a bottom plan view.

I claim:

The ornamental design for a shoe heel protector as shown and described.

IDA M. SNYDER.

Witnesses:

Mrs. W. T. RAMSAY,
VIRGINIA NOLAND.
